DEVICE FOR CLEANING QUILLS

Edgar Alexander McKillop, Hendersonville, N. C.

Application June 25, 1934, Serial No. 732,377

3 Claims. (Cl. 28—20)

This invention relates to a device for cleaning the central passages in quills and is an improvement of the device described and claimed in my Patent No. 1,945,654, granted Feb. 6, 1934.

5 Machines have been employed for removing the weft-residue windings upon the exterior of the quill or bobbin by means of scrapers or knives. Means are employed for feeding the quills or bobbins to the stripping apparatus and means are 10 also employed for removing the quills or bobbins after they have been cleaned. These machines are automatic in operation but they only partially clean the quills due to the fact that the interior of the quills carry some lint which must be removed to prevent this lint affecting the proper 15 positioning of the bobbin on its spindle. In some mills the quills or bobbins are cleaned manually by means of tools or wires which are inserted through the central bore but where the central 20 bore contains a great deal of lint these tools have a tendency to pack the lint and clog the central opening so that the quills or bobbins must be discarded as useless.

An object of the present invention is the provision of a device for cleaning the axial passages of the quills or bobbins by forcing compressed air through the passages when the quills are placed in operative position for the removal of the lint upon the exterior of the quills.

30 Another object of the invention is the provision of a compact and simple device which may be readily attached to a machine which is adapted to clean the weft residue from the exterior of quills or bobbins, the device being so constructed that the lint from the interior may be removed simultaneously by a sudden blast of compressed air through the central passage in the quill.

40 A further object of the invention is the provision of a device for forcing compressed air through the axial passages of quills or bobbins for removing lint collected therein in which a nozzle is provided having a slot for a portion of its length so that the quills may be readily dropped into the slot and be positioned in alignment with the air passage in the nozzle with means for automatically pressing the nozzle into sealed engagement with the end of the quill, the device including means for automatically releasing 45 a blast of compressed air through the nozzle and the quill at approximately a time when the nozzle has been pressed into operative relation with an end of the quill.

50 A still further object of the invention is the provision of a device for removing lint from the

interior of quills or bobbins in which a nozzle is moved into operative engagement with an end of a quill at a time when the quills are automatically received by the nozzle, said means including an air valve which is operated by a block 5 supported by a plurality of pivotal connections with a fixed support so that when the nozzle is shifted the block which is pivotally connected to the nozzle structure will be moved into operative engagement with the stem of an air valve for releasing air at the limit of movement of the reciprocating air nozzle.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Figure 1 is a side view in elevation of a quill cleaning device with parts in section,

Figure 2 is a plan view of the same,

Figure 3 is a transverse vertical section taken along the line 3—3 of Figure 1,

Figure 4 is a transverse vertical section taken along the line 4—4 of Figure 1,

Figure 5 is a transverse vertical section taken along the line 5—5 of Figure 1,

Figure 6 is a fragmentary vertical longitudinal section taken along the line 6—6 of Figure 2,

Figure 7 is a longitudinal vertical section of the air nozzle and support for a quill,

Figure 8 is a plan view of a modified form of the invention, and

Figure 9 is a longitudinal vertical section of the device shown in Fig. 8.

Referring more particularly to the drawings, 10 40 designates a table which forms a part of a bobbin stripper not generally shown for cleaning the lint from the exterior of the bobbins. Only those parts of a bobbin stripper disclosed in Patent No. 1,740,127, dated Dec. 17, 1929 are disclosed which 45 are necessary to show the adaptation of my device to said bobbin stripper.

A guide 13 has a depending flange 14 which is secured at 15 to the bracket 11. The guide is provided with bearings 16 and 17 which receive 50 a reciprocating pipe 18. One end of the pipe is provided with an air valve 20 which is connected with a flexible pipe 21 which may be formed of rubber or any other suitable material and this last-mentioned pipe is connected with a com- 55

- pressed air supply (not shown). The opposite end of the pipe is provided with a nozzle, generally designated by the numeral 22. The bearings 16 and 17 are located between the valve 20 and the nozzle 22. A collar 23 is secured at 24 to the pipe 18. The spring 25 embraces the pipe and is engaged between the bearing 16 and the collar 23 tending to force the pipe to the right in Fig. 1 to release the quill 26.
- 10 A nozzle 22, as shown in Fig. 7, is formed of a cylindrical member 30 having a cut-off portion 31 which provides an elongated slot or opening at the top of the nozzle in order that the quill 26 may be dropped in through this slot for engagement with the nozzle, the quill resting upon the portion 32. A pipe 18 is inserted within the cylindrical portion 30 and is secured in place by means of a set screw 33. A nipple 34 has a reduced passage 35 through which air from the pipe 18 is forced. A collar 36, formed of some resilient material which may be rubber, is inserted within the cylindrical portion 30 and receives the reduced end of the nipple 34. The nipple has a shoulder 37 which engages the inner face of the collar 36 so that when the pipe is forced into the cylindrical portion 30 and secured in place by the set screw 33, the nipple will be forced into engagement with the resilient collar 36. The inner wall of the cylindrical portion 30 is provided with a shoulder 38 which is engaged by the collar 36 and maintains the collar in position within the nozzle.
- 15 A block 40 having a central passage 41 which receives the pipe 18 is secured in place by means of a set screw 42 and this set screw provides a means for adjusting the block at various positions along the pipe 18 for a purpose which will be presently explained. The block is provided with axles 43 upon which are mounted rollers 44 and these rollers are adapted to be engaged by the arms of a fork 45 at the upper end of a lever 46.
- 20 A link 50 is pivotally connected at 51 to an enlargement 52 formed at one end of a rod 53. This rod is threaded, as at 54, and inserted through an opening in a depending arm 55 with nuts 56 on opposite sides of the arm for securing the rod 53 in position. The arm 55 forms an integral part of the guide 13. A block 60 is pivotally connected at 61 with the link 50 and also has pivotal connections at 62 with a bracket 63 extending downwardly and carried by the valve 20 as shown at 64. The bracket is rigidly secured to the valve 20. A valve stem 65 which operates the valve 20 has its free end projecting downwardly and in engagement with a shoulder 66 at the upper end of the block 60.
- 25 A cross head 70 which is reciprocated periodically and actuated by mechanism, not disclosed, is movable in a slot 71 in the table 10. This cross head carries a plunger 72 which is adapted to engage a head 73 on a reciprocating rod 74. The actuating mechanism for the cross head is a part of the bobbin stripper referred to above. This rod is supported in a bearing 75 secured at 76 to the depending arm 12. The rod is received by a passage 77 in the bracket 11 and is supported in a bearing 78 secured at 79 to the bracket 11. The end of the rod 74 adjacent the bearing 78 is provided with a head 80 in which, at 81, is pivotally mounted one end of a link 82.
- 30 The lever 46 is pivotally mounted at 85 on an arm 86 extending from the guide 13. The upper end of the lever, as has been stated, is provided with a fork 45 which embraces the pipe 18 and engages the rollers 44. The lower end of the lever is offset, as shown at 87, and is bifurcated at

35 88 to receive the link 82. A pin 89 is adapted to be received by any one of a plurality of perforations 90 in the link for connecting the lower end of the lever 46 to the link. It will also be noted that the lever 46 is provided with a passage 91 in 5 which the link 50 is oscillated.

The opposite end or head 100 of the quill 26 which has a central passage 101 is adapted to be grasped by the gripper jaws 102 and held in place so that the quill will be in substantially a horizontal position and with the opposite end 103 in alignment with the nozzle 22. The jaws 102 form no part of the present machine but are a part of the usual bobbin stripper (not shown). These jaws are as usual carried by the usual cross-head 15 which carries part 70.

A head 105 is adapted to abut the end 101 of the quill 26 so that the passage 101 in the quill will be aligned with the passage 106 in the head. This head is supported by a screw 107 formed 20 integrally with the head 105.

The operation of my device is as follows: The quills 26 are fed in a periodic manner to the head 105 and grasped by the jaws 102 and the member 32 of the nozzle 22 and the feeding 25 mechanism is timed in synchronism with the cross head 70 so that the quills will be deposited in their respective aligned supports just before the cross head is moved to the right.

When the cross head is moved to the right, as 30 shown in Fig. 1, the link 82 is moved in a similar manner and the lever 46 is rocked on its pivot 85 so that the upper end or fork 45 is moved to the left and since this fork is in engagement with the rollers 44, the pipe 18 will be moved 35 to the left as will be the nozzle 22 a sufficient distance that the reduced end of the quill 26 will be forced in snug relation with the rubber washer or collar 36, thereby making an air-tight connection between the reduced end of the quill and 40 the collar. The reduced end of the quill is supported on the member 32 while the slot 31 is of sufficient width to permit the reduced end of the quill to drop on to the member 32.

The pipe 18 is moved to the left against the 45 tension of the spring 25 through the collar 23 which is secured to said pipe so that when the rod 74 is moved to the left on its return movement the spring will return the pipe 18 to its 50 normal inoperative position.

As the pipe 18 is moved to the left the block 60 will be rocked due to its pivotal connections 61 and 62 respectively with the link 50 and the bracket 63. Since the link 50 is pivotally mounted at 51 the link will be permitted to rock and since the pivot 62 moves in a horizontal plane as the pipe is reciprocated the shoulder 66 on the block 60 will be elevated, thereby raising the stem 65 and opening the valve 20 to permit compressed 55 air to flow from the pipe 21 to the pipe 18 and through the quill 26.

It will be noted that a plurality of perforations 61^a are formed in the link 50 so that the position of the block may be varied. This is also 60 true of the link 82 since the pin 89 may be received by any one of the perforations 90 in the link and thereby varying the throw of the lever 46.

It may be necessary at times to change the 70 adjustment of the block 40 and this may be done by releasing the set screw 42 and moving the block towards or away from the bearing 17. By this variation and position of the block 40 the time of opening of the valve 20 may be varied 75

with respect to the engagement of the nozzle 22 with the reduced end of the quill 26.

It will be appreciated that after the lint has been blown through the central passage 101 of the quill 26 it will pass out through the passage 106 and be projected downwardly after which the nozzle 22 is returned to its inoperative position by the spring 25 and the quill 26 is removed to permit the application of other quills.

10 The device shown in Figs. 8 and 9 is one which is adapted to be attached to the push head of the Terrell quill stripper disclosed in one form in Patent 1,740,128, dated Dec. 17, 1929.

15 In this instance a table 150 is provided having a longitudinal slot 151 and a depending flange 152. This table forms a part of the quill stripper.

20 A traveling push head 153 is mounted on the table 150 and is moved back and forth by means of ears 154 connected with a crank arm 154^a which is connected with the stripper and reciprocated back and forth for causing the push head to be operated. This mechanism forms no part of the present invention and therefore no further description appears necessary.

25 Mounted on the push head 153 is a push head block 155 which is adjustable longitudinally of the push head 153 and this adjustment is provided by means of a slot 156 formed longitudinally of the slide and through which projects a pipe 157 having a threaded portion 158 upon which is threaded a nut 159 for holding a corrugated washer 160 in engagement with a knurled or ribbed surface 161. The upper end of the pipe is also threaded into an opening 162 formed in the bottom portion of the push head block 155. When it is desired to adjust the block longitudinally of the slide 153 to provide for quills of various sizes, the nut 159 is loosened and the block and the pipe 157 are moved along the slide with 40 the pipe riding in the slot 156. When the proper position of the block has been procured the nut is again screwed into position.

30 The block is provided with a socket or bobbin tip seat 163 adapted to receive the small end of the quill with the longitudinal passage in the quill being adapted to be aligned with a passage 164 which communicates with the passage 162 and the pipe 157.

35 The pipe 157 is placed in communication with a valve casing 165 by means of a pipe 166 and an elbow 167. This valve casing contains a valve which is operated by a stem 168 projecting beyond the valve casing.

40 A lever 170 is pivotally mounted at 171 at its upper end on a bracket 172 which is secured to the valve casing 165. This lever is provided with a toe 173 which is adapted to engage the projecting end of the valve stem 168. The lower end of the lever is bifurcated at 174 and spans one end of a link 175. The bifurcated portion of the lever is pivoted at 176 to the end of the link.

45 The link is provided with an abutment 177 and is retained in position on the outer end of the link by means of a bolt 178 which may be placed in any one of a plurality of perforations 179 formed in the end of the link 175 to provide for the change in position of the abutment 177. This adjustment of the abutment is necessary where quills of different lengths are employed as will be presently seen.

50 The link 175 at its outer end projects through a passage 180 formed in the bottom of a bar 181

which is secured at 182 to the flange 152. The inner end of the abutment 177 engages an enlargement 183 formed on the outer face of the bar 181.

5 The operation of my device is as follows: The quills are fed to the stripper automatically in a well known manner and as the push head 153 is reciprocated to the right in Fig. 9, the abutment 177 moves away from the boss 183 or the bar 181 with the link 175 moving through the slot 180. At this time the lever 170 is rocked with the lower end of the lever being moved to the left so that the toe 173 will be moved away from the stem 168 of the valve. At this time as is well known the quill will be removed from the push head block 155 and as the push head 153 is moved towards the left another quill drops in position with the small end of the quill being received by the socket 163 and the open end of the quill will be in alignment with the passage 164. Continued movement of the push head to the left will carry the pipes 157 and 166 and the flexible hose 190 which is connected to a source of air under pressure also to the left and the link 175 will also be drawn to the left carrying the abutment 177 towards the boss 183. At this time, however, there will be no pressure exerted on the lever 170 so that the valve in the casing 165 will not be operated by the stem 168. However, after the head 153 has been moved within a fraction of an inch 30 of its limit of movement, the abutment 177 is so positioned on the link 175 that it will come in contact with the boss 183 and hold the link 175 against further movement. This will cause the lever 170 to be rocked and the toe 173 will operate the valve stem 168 and open the valve in the casing 165 and cause a blast of air to be discharged from the passage 164 through the quill, thereby blowing out the waste from the interior of the quill and thus prevent such lint from being 40 carried in the manufactured cloth.

35 The blast, however, is only momentary since the push head is returned immediately to the right to permit closing of the valve. The speed of operation is rapid so that no prolonged blowing is had nor is it required.

45 What I claim:

1. In combination with a bobbin stripper of the type employing a sliding cross-head carrying a pair of gripping jaws for gripping the head of the bobbin to draw it through the usual scraping knives, a slideable tube carrying a nozzle at the end adapted to engage the tip of the bobbin while the same is grasped by said jaws, the tube being connected at its other end to a source of compressed air, a valve in said tube, and means actuated by the forward movement of said cross-head to not only advance said tube to put its nozzle into contact with the tip end of the bobbin but also to open said valve.

2. The structure cited in claim 1, said means embodying a slideable rod actuated by said cross-head, a lever associated with the tube and actuated by said rod.

3. The structure recited in claim 1, said means embodying a spring positioned and arranged to be tensioned by said forward movement of the cross-head and released by the return movement of the cross-head to restore all the parts to normal position.
